UNITED STATES PATENT OFFICE

2,379,143

NOISEMAKING DEVICE

Truman Gile, Miami Springs, Fla.

Application August 3, 1944, Serial No. 547,831

4 Claims. (Cl. 46—191)

My invention relates to improvements in noise-making devices, of the percussion type, for toy guns, the primary object in view being to provide simply constructed, inexpensive devices for incorporation in present day toy guns to produce a sound similar to that resulting from the discharge of a cartridge, and which are double-acting for maximum speed of sound production, and proof against mis-operation tending to damage or impair the efficiency thereof.

Other and subordinate objects are also comprehended by my invention, all of which, together with the precise nature of my improvements, will be readily understood when the succeeding description and claims are read with reference to the drawing accompanying and forming part of this specification.

In said drawing:

Figure 1 is a fragmentary view in longitudinal section of a toy gun equipped according to my invention with the combined trigger and cocking plate in substantially the forward limit of movement thereof,

Figure 2 is a similar view with said plate in an intermediate position,

Figure 3 is another similar view showing said plate in the rearward limit of movement thereof.

Referring to the drawing by numerals, my improved noise-making device has been shown therein as embodied in a toy gun having a stock 1 surmounted by a barrel breech section 2 from which a hand grip post 3 depends forwardly of the stock 1. A T-shaped, through slot 4 is provided in the breech section 2 extending longitudinally in the plane of the gun.

The slot 4 opens onto the top of said breech section 2 and onto the bottom of said section, between the stock 1 and the hand grip post 3, and forms in said section a pair of flat front and rear stop ledges 6, 7 at the front and rear ends of said slot 4, respectively.

A flat percussion bar 8 of resilient material, such as suitable wood, extends flatwise along the breech section 2 at the top of the slot 4 and is fixed intermediate its ends in said slot to provide upwardly flexible front and rear ends 9, 10 on said bar adapted to react downwardly when cocked and to impact the breech section 2 upon opposite sides of the slot 4 to produce a loud noise. A transverse pin 11 extending through a central block 12 on said bar 8 and into the breech section 2 fixes the percussion bar 8 to said section.

A combined cocking and trigger plate 13 of substantially T shape is pivotally and slidably mounted, as presently described, in said breech

section 2 and slot 4, below the percussion bar 8, for vertical rocking in opposite directions, respectively, and sliding in opposite directions in the plane of the gun into forward and rearward limits of movement, respectively. The mounting for said plate 13 comprises a longitudinal slot 14 therein and a cross pin 15 extended through said slot 14 with its ends suitably anchored in the breech section 2. The combined cocking and trigger plate 13 comprises a pair of front and rear, right angled cocking dogs 16, 17, a trigger grip 18 depending through the bottom of the slot 4, and a finger hole 19 therein forwardly of the trigger grip 18. The front and rear dogs 16, 17 are spaced apart a distance slightly less than the length of the percussion bar 8 and arranged to abut the front and rear ends 9, 10 of said bar alternately, as will presently be clear.

Referring now to the operation of the described invention, when the combined cocking and trigger plate 13 is moved forwardly by means of the trigger grip 18 and finger hole 19 into its forward limit of movement as established by the slot and pin 14, 15, said plate is rocked counterclockwise, as viewed in Figure 1, to swing the front dog 16 upwardly in front of the front end of the percussion bar 8, and to position the rear dog 16 beneath and engaging the rear end 10 of said bar 8, the rocking movement being limited by engagement of the rear dog 17 with the rear ledge 7. By rearward pull exerted against the trigger grip 18, the front dog 16 is caused to abut the front end of the percussion bar 8 and then swing downwardly against the front ledge 6 to release said front end of the bar. During this operation, and until release occurs, the rear dog 17 flexes the rear end 10 of said bar 8 upwardly into cocked position, as shown in Figure 2. As soon as release occurs, the plate 13 under the pull on the same slides rearwardly until the rear dog 17 moves from under the rear end 10 of said bar 8, whereupon said end 10 reacts downwardly out of cocked position, impacts the top of the breech section 2 and produces a loud noise. By pushing forwardly on the trigger grip 18, or in other words, plate 13, the described operation is reversed to cause cocking of the front end 9 of the percussion bar and the subsequent release thereof by the front dog 16, all in a manner which, it is believed, will be clear.

As will now be seen, the device is double acting and cannot be accidentally cocked so as to impair its operation, and is well adapted to rapidly produce loud sounds resembling that of a cartridge being fired. As will also be apparent, the inven-

tion involves a minimum number of parts which are inexpensive to manufacture and which may be easily incorporated in present day toy guns.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a toy gun, a breech barrel section having a longitudinal through slot therein, a percussion bar fixed in said slot to extend along the top of said section and having front and rear ends flexible upwardly into cocked position for reaction downwardly against said section to produce a loud sound, and manipulative means for flexing said ends of the bar into cocked position and releasing the same alternately.

2. In a toy gun, a breech barrel section having a longitudinal through slot therein, a percussion bar fixed in said slot to extend along the top of said section and having front and rear ends flexible upwardly into cocked position for reaction downwardly against said section to produce a loud sound, and manipulative means for flexing said ends of the bar into cocked position and releasing the same alternately comprising a combined cocking and trigger plate pivotally and slidably mounted in said slot.

3. In a toy gun, a breech barrel section having a longitudinal through slot therein, a percussion bar fixed in said slot to extend along the top of said section and having front and rear ends flexible upwardly into cocked position for reaction downwardly against said section to produce a loud sound, and manipulative means for flexing said ends of the bar into cocked position and releasing the same alternately comprising a combined cocking and trigger plate pivotally and slidably mounted in said slot, and including a pair of front and rear dogs for coaction with said front and rear ends of said bar to cock and release the same.

4. In a toy gun, a breech barrel section having a longitudinal through slot therein, a percussion bar fixed in said slot to extend along the top of said section and having front and rear ends flexible upwardly into cocked position for reaction downwardly against said section to produce a loud sound, and manipulative means for flexing said ends of the bar into cocked position and releasing the same alternately comprising a combined cocking and trigger plate pivotally and slidably mounted in said slot, and including a pair of front and rear dogs for coaction with said front and rear ends of said bar to cock and release the same, said slot having front and rear ledges therein for coaction with said dogs to limit pivotal movement of said plate.

TRUMAN GILE.
